AIR CONDITIONING FAN

Benjamin C. Bartlebaugh, Wheeling, W. Va.

Application February 21, 1936, Serial No. 65,145

3 Claims. (Cl. 230—273)

The present invention is directed to improvements in portable air conditioning fans, and more particularly to one designed to be placed on a heating unit, such for instance as a gas heater, hot air register or a radiator.

The primary object of the invention is to provide a device of this character so constructed that when placed on a heating unit the heated air rising therefrom will propel the fan with sufficient velocity to draw air from all parts of the room in which it is placed, and from adjacent rooms, the air thus drawn being subjected to the action of the fan to cause circulation thereof to condition the same.

Another object of the invention is to provide a device of this kind which is extremely simple in construction, efficient in operation, and one which can be manufactured at a small cost.

With these and other objects in view, this invention resides in the novel features of construction, formation, combination and arrangement of parts to be hereinafter more fully described, claimed, and illustrated in the accompanying drawings, in which:

Figure 1 is a side elevation of the device.

Figure 2 is a top plan view thereof.

Figure 3 is a perspective view of the device, the fan being removed.

Figure 4 is a vertical sectional view through the device.

Figure 5 is a sectional view on line 5—5 of Fig. 1.

Referring to the drawings, 1 designates a base formed from suitable gauge sheet metal, the base being hollow to constitute a fresh air chamber 2, fresh air being admitted to the chamber through openings 3 formed in the side walls 4 of the base.

The top 5 of the base is provided with a centrally located opening 6, and into which is fitted the lower end of a collar 7. This collar is retained in place by a pair of brackets 8 consisting of angularly disposed arms 9 and 10, the former being secured to the top 5 by bolts 11, while the latter are extended into the collar and are secured thereto by rivets 12.

A sleeve 13 is removably engaged on the collar 7, the lower end thereof resting on the top 5, said sleeve being of greater length than the collar, and constitutes an air discharging duct.

Extending transversely of the sleeve 13, and near the top thereof is a bar 14 having hooks 15 on its ends adapted to fit on the upper edge of the sleeve, the arms 16 thereof resting against

the inner surface of the sleeve while the arms 17 lie against the outer surface thereof.

A second bar 18 is employed and has downturned ends 19. The ends of this bar rest on the hooks 15 and the terminals or ends 19 rest against the arms 17, and securing devices 20 are passed through the ends 19, arms 17 and sleeve 13 to hold the parts in assembled relationship.

The bar 14 is provided with a central opening 21, and through which extends the shank of the pin 22, the head 23 thereof serving to prevent upward movement of the pin. To retain the pin 22 in true perpendicular position a metal strip 24 is employed and has its ends riveted to the undersurface of the bar 14 in order that the head 23 will be firmly engaged by the strip to retain the pin in place.

The pin 22 extends through a bearing 25 formed centrally in the bar 18 and is in direct alignment with the opening 21 of the bar 14 in order that the bar 18 will effectively brace the pin to maintain the same in vertical position.

The fan 26 includes a hub 27 and integral blades 28, there being an opening 29 in the hub which coincides with an opening 30 formed in the plate 31, said plate engaging the under surface of the hub to brace the same.

An inverted sheet metal cup 32 is employed and has a flange 33 adapted to rest on the hub 27, said cup being fitted in an opening 34 formed in the top plate 35, said plate being secured to the flange 33, hub 27 and plate 31 by rivets 36, additional rivets 37 being used to secure the margin of the plate 35 to the hub 27 and plate 31.

In the top of the cup 32 is fixed a shank 38 having a head 39 on its lower end, said shank and head being formed from hardened steel, the purpose of which will be obvious as the description proceeds.

A sheet metal partition 40 is suitably fixed in the cup 32, and is provided with a central opening 41 alined with the openings 29 and 30 of the hub 27 and plate 31, respectively. The partition provides a grease chamber 42 within the cup, grease being introduced thereto through openings 43 in said cup.

As clearly shown in Fig. 5 of the drawings the pin 22 extends through the openings 30, 29 and 41 and its pointed end engages the head 39, due to which resistance to rotation of the fan 26 is practically nil.

The presence of the grease chamber 43 assures proper lubrication of the pin 22, and the fact that the pin is engaged in the opening 41 of the

partition 40 aids in balancing the fan 26 on said pin.

The fan 26 can be easily removed from the pin 22 when desired and replaced thereon easily and quickly.

Briefly the operation is as follows:

Heat rising from the unit upon which the base 1 is placed will propel the fan, and during the propulsion thereof air from the room in which 10 the device is located will be drawn through the openings 3 and will enter the base and then flow upwardly in the sleeve 13 for discharge from the upper end thereof. In this manner the fan will agitate the air to condition the same by thorough circulation.

What is claimed is:

1. A portable air conditioner comprising a hollow base, a collar supported by the base, a sleeve supported by the base and encircling the collar, 20 said collar and sleeve communicating with the interior of the base, upper and lower vertically spaced bars supported by the sleeve and disposed transversely thereof, a pin having its low-

er end engaged with the lowermost bar and extending through the upper bar, a fan having a cup fixed to its hub, a partition in the cup to define a chamber therein, a head in the chamber, said pin passing through the partition and 5 rotatably engaged with said head.

2. A portable air conditioner comprising a hollow base, a sleeve supported thereon, a pin supported axially of the sleeve, a fan having an inverted cup fixed to its hub, a partition in the 10 cup defining a chamber therein, said pin passing through the hub and partition for rotatably engaging the cup.

3. A portable air conditioner comprising a hollow base, a sleeve supported thereon, a pin supported axially of the sleeve, a fan having an inverted cup fixed to its hub, a partition in the 15 cup defining a chamber therein, said pin passing through the partition and rotatably engaged with the cup, the side walls of the base having openings therein, as and for the purpose set forth.

BENJAMIN C. BARTLEBAUGH.
